GOLF CART

Bernard E. Post, 424 S. 12th, Clear Lake, Iowa

Filed July 2, 1965, Ser. No. 86,012

Term of patent 14 years

(Cl. D14—3)

FIG. 1

FIG.2

FIG.3

FIG.4

FIG.5

FIG. 6

FIGURE 1 is a front perspective view of a golf cart constructed in accordance with a first embodiment of my invention;

FIGURE 2 is a side elevation of the golf cart shown in FIGURE 1;

FIGURE 3 is a top view of the golf cart shown in FIGURE 1;

FIGURE 4 is a front view of the golf cart shown in FIGURE 1;

FIGURE 5 is a rear view of the golf cart shown in FIGURE 1, and

FIGURE 6 is a perspective view of a golf cart constructed in accordance with a second embodiment of my invention.

The dominant features of my design reside in the portions thereof shown in full lines in the drawings. The golf bags and clubs shown in broken lines are included for illustrative purposes only.

I claim:

The ornamental design for a golf cart, substantially as shown and described.
